UNITED STATES PATENT OFFICE.

JAMES C. ANDERSON, OF HIGHLAND PARK, ILLINOIS.

METHOD OF PREPARING BRICK FOR TRANSPORTATION TO MARKET.

SPECIFICATION forming part of Letters Patent No. 389,043, dated September 4, 1888.

Original application filed August 18, 1887, Serial No. 247,204. Divided and this application filed April 19, 1888. Serial No. 271,194.
(No model.)

To all whom it may concern:

Be it known that I, JAMES C. ANDERSON, a citizen of the United States of America, residing at Highland Park, in the county of Lake 5 and State of Illinois, have invented certain new and useful Improvements in the Method of Burning, Packing, and Transporting Brick, of which the following is a specification, reference being had therein to the accompanying 10 drawing.

My invention relates to improvements in the method of burning, packing, and transporting bricks to market.

In an application for a patent filed by me 15 August 18, 1887, Serial No. 247,205, I have claimed the method of burning brick in continuous kilns by passing two trains of cars loaded with the brick to be burned through tunnels in opposite directions past suitable 20 furnaces, which burn the brick to the proper point, the heated and burned portions of each of the brick bodies being utilized to heat and water-smoke the brick in the other column or body.

25 In another application for a patent, filed by me August 18, 1887, Serial No. 247,204, I have shown, described, and claimed a kiln for burning fine brick, in which the principles of the invention claimed in application No. 247,205 30 are utilized, only such changes being made as are necessary to prevent the fumes of the products of combustion from coming in contact with the brick.

This application being a division of application No. 247,204, the invention hereof consists in the method hereinafter described of hacking the bricks to be burned on cars in 35 rows, with intervening spaces, and after the brick are burned packing hay, straw, or other 40 suitable material into the spaces to hold the brick in their place, whereby frequent handlings of the brick are dispensed with and the cars adapted to be transported any desired distance without injury to the brick.

45 In the drawing herewith annexed I have shown in side elevation the top or body of the car with the bricks piled thereon and the spaces between the piles of bricks filled with straw or hay.

A indicates the body of the car, which may 50 be of special construction, but preferably of the ordinary gondola type used generally on railroads. The floor or bottom of the car is protected from the injurious effects of the heat from the furnaces by layers of asbestos, felt, 55 and sheet metal and a layer or layers of fire-proof tiles, A', on which the brick to be burned are stacked, said tiles being held in position by the angle-irons B. These angle-irons B also serve to hold the body C of the car, as 60 shown in dotted lines, the car-body being placed thereon after the bricks have been burned. The bricks are piled in rows across the car flatwise and lengthwise, one layer immediately above and on top of the other, so as 65 to allow a free space, D, from top to bottom between each of the rows or piles, said spaces not only serving to allow the heat from the furnaces to readily reach the brick to perfectly burn the same, but also to receive the hay, 70 straw, or other suitable packing material, E, which is forced into the spaces after the car is removed from the kiln and the bricks have become sufficiently cool, so as not to ignite the packing material.

75 The bricks may be packed in rows of two laid side by side, and, as before stated, flatwise and lengthwise across the car, care being taken to place the face edge of the brick outward or toward the open spaces, so 80 that this edge will be in contact with the straw or other packing material, and the face edges will not rub against the adjacent brick, and thus all danger of injuring the brick in transporting the same to market is obvi- 85 ated.

Another important advantage gained by this process is that the usual frequent handlings of the brick are dispensed with. The only handling of the brick occurs when they are 90 taken from the machine and stacked on the car, no other handling taking place until the bricks are delivered in the market.

What I claim, and desire to secure by Letters Patent, is—

95 The method herein described of preparing brick for transportation to market, which consists in hacking the brick on a car in piles,

with intervening spaces between the piles, and
burning the bricks on said car, and in then
packing hay, straw, or other suitable material
into the spaces between the piles of brick,
5 whereby a separate handling of the brick to
prepare them for safe transportation is dis-
pensed with.

In testimony whereof I affix my signature in
presence of two witnesses.

J. C. ANDERSON.
